UNITED STATES PATENT OFFICE.

JOHN FRANKLIN KILBURN, OF EL PASO, TEXAS, ASSIGNOR OF ONE-HALF TO GEORGE E. WALLACE, OF EL PASO, TEXAS.

PUMP WORKING BARREL.

1,078,444.

Specification of Letters Patent. Patented Nov. 11, 1913.

Application filed February 27, 1913. Serial No. 750,985.

To all whom it may concern:

Be it known that I, JOHN FRANKLIN KILBURN, a citizen of the United States, and a resident of El Paso, in the county of El Paso and State of Texas, have invented a new and Improved Pump Working Barrel, of which the following is a full, clear, and exact description.

This invention relates to pumping apparatus and has particular reference to the specific construction of working barrels for any kind of pumps in which there are movable or reciprocating pistons.

Among the objects of this invention is to construct a cylinder or working barrel in such a manner and of such material as to increase its reliability and durability.

More particularly stated, the object of the present invention is to construct a pump cylinder of glass whereby the friction of the piston is reduced to a minimum and to so mount the cylinder with respect to the other portions of the pump as to make it thoroughly reliable in all practical operations.

The foregoing and other objects of this invention will hereinafter be more fully described and claimed and illustrated in the drawings forming a part of this specification in which like characters of reference indicate corresponding parts in all the views, and in which—

Figure 1 is a vertical sectional view illustrating a preferred embodiment of the invention; Fig. 2 is a transverse section on the line 2—2 of Fig. 1; and Fig. 3 is a fragmentary vertical section of a modified form.

Except as otherwise stated, the several parts of the invention may be made of any suitable materials and the relative sizes and proportions thereof, as well as the general design of the device, may be varied to a considerable extent without departing from the spirit of the invention hereinafter claimed.

Referring more particularly to the drawings, I show at 10 a pump cylinder constructed preferably of glass and formed with a central bore 11 for the accommodation of a plunger 12. Said plunger may be made of any suitable design having a plurality of flexible packing washers 13 and also being provided with a sucker valve 14.

A sucker rod 15 of any suitable construction is extended downwardly through the pump casing 16 as usual and is connected to the 55 plunger.

A pair of heads 17 and 18 are connected to the upper and lower ends of the cylinder respectively, each of said heads being provided with outwardly extending lugs 19 and 60 each also having a centrally bored hub 20 abutting against and alining with the adjacent end of the cylinder.

A shell 21 preferably of metal and made in several parts, is applied to the outside of 65 the cylinder 10, and the shell parts extend beyond the ends of the cylinder into embracing coöperation with said hubs 20 of said heads, as shown especially in Fig. 1. I also preferably employ a filler or plastic 70 packing 22 between the inner surface of the shell and the outer surfaces of the cylinder and hubs and a similar packing 22' between the ends of the cylinder and the hubs.

Any suitable means may be employed to 75 secure the parts of the shell in place and thereby secure the cylinder in place and protect it from outside damaging influences. For this purpose I may employ a plurality of sets of rings 23 and 24. The rings 23 are 80 preferably split lengthwise of the cylinder and the material thereof in cross section is tapered, as indicated in the drawings, and the ring as a whole is provided with an external screw thread. The ring 24 is a solid 85 ring made either in one piece or in several pieces clamped together, and being provided with an internal thread and larger than the ring 23 is adapted to be screwed or turned over said ring 23, and because of the taper 90 of the coöperating parts, the screwing of the outer ring 24 upon the inner ring 23 will produce a substantial binding or clamping effect upon the portions of the shell 21. Each of the rings 23 is preferably provided 95 at its ends with smooth or blank portions 25 and 26, the former being for the purpose of facilitating the assembling of the pair of rings and the latter providing for the application of a wrench or other holding tool. 100

In one form of the invention the heads 17 and 18 are clamped in place against the ends of the cylinder by means of a series of tie rods 27 having nuts on one or both ends

whereby tension may be applied to the rods in an obvious manner, said rods passing through the lugs 19.

The head 18 is preferably provided with a 5 tapered bore 18' which constitutes a seat for the foot valve 28.

That form of the invention illustrated in Fig. 3 consists of a cylinder shell 21' having its ends substantially flush with the ends 10 of the cylinder provided with an external screw thread for direct engagement with an internally threaded flange 29 of the adjacent head 17'. It will be understood, of course, that the head at the bottom of the 15 cylinder will be made ordinarily in the same manner, and by reason of the flanged connection between the heads and the cylinder shell, the tie rods need not be used. The head 17' is provided preferably with a neck 20 30 for direct connection of the pump casing similar to the manner of connecting the pump casing to the head 17 previously described.

Having thus described my invention, I 25 claim as new and desire to secure by Letters Patent:—

1. In a working barrel for pumps, the combination of a cylinder, a pair of heads having hubs bearing against the respective 30 ends of the cylinder, a shell longer than the cylinder and surrounding the cylinder and said hubs, plastic packing between the shell and hubs and the cylinder, means to grip

the shell around the cylinder, and means to draw the heads toward each other into binding contact with the ends of the cylinder, substantially as set forth. 35

2. In a working barrel for pumps, the combination of a cylinder, a shell surrounding the cylinder, and means to secure the 40 shell detachably in position, said securing means comprising a pair of rings, one of said rings being split and provided with an external thread and the other ring being rigid and provided with an internal thread 45 for coöperation with the external thread aforesaid, substantially as set forth.

3. In a working barrel for pumps, the combination of a cylinder, a shell surrounding the cylinder, and means to secure the 50 shell detachably in position, said securing means comprising a pair of rings, one of said rings being tapered and having smooth ends and also having an external thread between such smooth ends, and the other ring 55 being provided with an internal thread co-operating with said external thread of the other ring, substantially as set forth.

In testimony whereof I have signed my name to this specification in the presence of 60 two subscribing witnesses.

JOHN FRANKLIN KILBURN.
